(57) **CLAIM**

The ornamental design for an earphones charging box, as shown and described.

DESCRIPTION

FIG. 1 is a perspective view of an earphones charging box showing our new design.

FIG. 2 is a front view of an earphones charging box.

FIG. 3 is a rear view of an earphones charging box.

FIG. 4 is a left side view of an earphones charging box.

FIG. 5 is a right side view of an earphones charging box.

FIG. 6 is a top view of an earphones charging box.

FIG. 7 is a bottom view of an earphones charging box; and,

FIG. 8 is a perspective view of an earphones charging box, shown in the open state.

The broken lines in FIG. 8 depict portions of the earphones charging box that form no part of the claimed design. The broken lines depicting earphones in FIG. 8 represent environmental subject matter that forms no part thereof.

1 Claim, 8 Drawing Sheets
